DESIGN FOR A SANDAL OR SIMILAR ARTICLE

Jacob Stein, New York, N. Y.

Application November 3, 1936, Serial No. 65,660

Term of patent 14 years

To all whom it may concern:

Be it known that I, Jacob Stein, a citizen of the United States, residing in the city, county, and State of New York, have invented a new, original, and ornamental Design for a Sandal or Similar Article, of which the following is a specification, reference being had to the accompanying drawing, forming a part thereof.

The figure is a perspective view of a sandal or similar article, showing my new design, both sides of which are identical save for the closing means for the ankle closure.

The front part of the upper consists of separate and narrow lateral ribbons, and a longitudinal band of contrasting material is superposed upon said ribbons, and forms the visible median longitudinal part of the upper. The ankle closure may be made of the same material as said band.

The heel part of the upper is made of separate narrow horizontal ribbons.

The essential feature of the design is the combination of said band and the ankle closure.

I claim:

The ornamental design for a sandal or similar article substantially as shown and described.

JACOB STEIN.
